RUFFLING MECHANISM FOR SEWING MACHINES

Andrew B. Clayton, Union, N. J., assignor to The Singer Manufacturing Company, Elizabeth, N. J., a corporation of New Jersey

Application March 10, 1932, Serial No. 597,881

5 Claims. (Cl. 112—132)

This invention relates to sewing machine ruffling mechanisms, more particularly of the type represented in the patent to Clayton, No. 1,815,881, of July 21, 1931, and has for an object to provide such a mechanism with means under the control of the operator for instantly changing the stroke of the ruffling blade from one to another value between predetermined limits and for instantly permitting one of said limits to be exceeded at the will of the operator.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 is a rear end elevation of a sewing machine embodying the invention. Fig. 2 is a side view of the parts adjacent the sewing point. Fig. 3 is a fragmentary front elevation of the parts shown in Fig. 1, and Fig. 4 is a horizontal section through the sewing machine bracket-arm standard, showing the parts of the device in top plan.

In the embodiment of the invention illustrated, there is used a sewing machine having a bed 1, from which rises the standard 2 of the usual goose-neck terminating in the head 3 in which is mounted the usual reciprocating needle-bar 4 and presser-bar 5 carrying, respectively, the needle 6 and presser-foot 7. The machine has a raised cloth-plate 8 below which and above the bed 1 is journaled the main shaft 9 carrying the ruffer-actuating eccentric 10 and balance-wheel 11.

The ruffer mechanism adjacent the head 3 is old, per se, and comprises the usual separator-plate 12 above which works the ruffer-blade 13 pivoted at 14 to the lower end of the ruffer-arm 15 fixed to the forward end of the ruffer rock-shaft 16 which is journaled horizontally in bearings 17 and 18 at the front side of the goose-neck. The rock-shaft 16 has fixed to it a curved crank-arm 19 which, in the advanced position of the ruffer-blade 13, is concentric with the axis of the main-shaft 9. The crank-arm 19 is actuated by the vertical pitman 20 which at its lower end embraces the actuating eccentric 10. The pitman 20 is pivotally connected at its upper end at 21 to a guide-head 22 preferably constructed substantially in accordance with the disclosure of the Clayton Patent No. 1,815,881, pre-

viously referred to. The guide-head 22 is slotted to receive and slide upon the curved arm 19 toward and away from the rock-shaft 16. It will be evident that the closer the guide-head 22 is moved to the rock-shaft 16 the greater will be the amplitude of the reciprocations imparted to the ruffling blade 13 by the pitman 20. The guide-head 22 is connected by means of the link 23 to the arm 24 of a manually operated bell-crank lever 24, 25 fulcrumed at 26 on the standard 2. A suitable pull-chain 27 extends from the bell-crank lever-arm 25 to a suitable pedal or knee-shift, not shown. The bell-crank lever 24, 25 is biased in a clockwise direction, Fig. 1, or in opposition to the pull of the chain 27, by the spring 28 which is coiled about the fulcrum-screw 26 and is anchored at one end 29 in the bearing bracket 18 and at its other end 30 is hooked under the arm 25. The downward motion of the arm 25 to increase the stroke of the ruffling blade 13 is limited by the stop 31 which is in the form of an L-shaped member, the shank 32 of which is received in a vertical guideway 33 in the bearing bracket 18. A screw 34 passing through a slot 35 in the stop-shank 32 is threaded into the bearing bracket 18 to hold the stop 31 in any desired position of vertical adjustment to predetermine the maximum desired ruffling stroke.

The minimum desired ruffling stroke is predetermined by the vertically adjustable stop-shoulder 36 formed on the stop-arm 37 which is pivotally mounted by means of the screw 38 upon the stop-carrier bracket 39 having a vertical rib-and-groove sliding engagement 40 with the bracket 18. The stop-carrier bracket 39 is formed with a slot 41 through which passes a holding screw 42 to clamp the stop-carrier bracket 39 in any desired position of vertical adjustment upon the bearing bracket 18. The stop-member 37 is provided with a downward extension or handle 43 which may be grasped at any time by the operator and shifted to the dotted line position shown in Fig. 3 to remove the stop-shoulder 36 from its position blocking upward movement of the bell-crank lever arm 25 under the influence of the biasing spring 28. When the stop 36 is shifted to one side of the bell-crank lever-arm 25, the guidehead 22 is moved by the spring 28 to its extreme position adjacent the free end of the curved arm 19 and the stroke of the ruffler-blade 13 is reduced to a small value less than the normal feed-stroke of the feed-dog 7' and hence produces no ruffle and is ineffective. The stop-arm 37 is free on the screw 38 and is gravity biased to swing

automatically from its dotted line to its full line position, Fig. 3, when the bell-crank lever-arm 25 is pulled downwardly by the operator to a position within its normal range of movement between the stops 31 and 36.

Having thus set forth the nature of the invention, what I claim herein is:—

1. In a ruffing attachment, a reciprocating ruffing blade, means for reciprocating said blade, means including a manually operated control-lever for determining the amplitude of the reciprocations of said blade, and a pair of stops for limiting the movements of said control-lever in opposite directions, one of said stops being in the form of a manually swingable pivoted lever having a stop-shoulder which is shifted at will out of the path of said manually operated lever.
2. In a ruffing attachment, a reciprocating ruffing blade, means for reciprocating said blade, means including a manually operated control-lever for determining the amplitude of the reciprocations of said blade, and a pair of stops for limiting the movements of said control-lever in opposite directions, one of said stops being in the form of a manually swingable pivoted lever having a stop-shoulder which is shifted at will out of the path of said manually operated lever, said pivoted lever being biased to return automatically to stopping position.
3. In a ruffing attachment, a reciprocating ruffing blade, means for reciprocating said blade, means including a manually operated control-lever for determining the amplitude of the reciprocations of the ruffing blade, and a pair of stops for limiting the movements of said control-lever in opposite directions, one of said stops being shiftably mounted for movement by the

operator in a direction to one side of the path of movement of said control-lever to permit the normal range of movement of said control-lever to be exceeded, said stop being biased to return automatically to a predetermined stopping position in the path of movement of said control-lever when said lever is returned to a position within its normal range of movement.

4. In a ruffing attachment, a reciprocating ruffing blade, means for reciprocating said blade, means including a manually operated control member for determining the amplitude of the reciprocations of said blade, a spring for biasing said manually operated control member in one direction, and a stop for limiting the movement of said control member under the influence of its spring, said stop being manually shiftable out of the path of movement of said control member and biased to return automatically to stopping position in such path.

5. In a ruffing attachment, a reciprocating ruffing blade, means for reciprocating said blade, means including a manually operated control member for determining the amplitude of the reciprocations of said blade, a spring for biasing said manually operated control member in one direction, a stop for limiting the movement of said control member under the influence of its spring, said stop being manually shiftable out of the path of movement of said control member and biased to automatically return to stopping position in such path, and means permitting adjustment of said stop to vary the position of said control member when in engagement therewith.

ANDREW B. CLAYTON.
